UNITED STATES PATENT OFFICE.

FRANK KUHN AND FRANK E. SHAILOR, OF DETROIT, MICHIGAN, ASSIGNORS TO AMERICAN ELECTRICAL HEATER COMPANY, OF DETROIT, MICHIGAN, A CORPORATION OF MICHIGAN.

THERMOSTAT.

1,107,316.

Specification of Letters Patent. Patented Aug. 18, 1914.

Application filed December 2, 1909. Serial No. 531,102.

To all whom it may concern:

Be it known that we, FRANK KUHN and FRANK E. SHAILOR, citizens of the United States of America, residing at Detroit, in the county of Wayne and State of Michigan, have invented certain new and useful Improvements in Thermostats, of which the following is a specification, reference being had therein to the accompanying drawings.

10 The invention relates to thermostats, and has for its object the obtaining of a mechanical construction free from delicate and easily disarranged parts, and positive in its operation.

15 To this end, the invention consists, first, in the construction of mechanism having a thermostatically-controlled friction lock; further, in the peculiar construction, arrangement and combination of parts, as 20 hereinafter set forth.

In the drawings—Figure 1 is a plan view of the thermostat as applied for controlling an electric switch; Fig. 2 is a similar view showing the switch in tripped position; Fig. 25 3 illustrates the application of the thermostat to an electrically-heated sad iron; Fig. 4 is a longitudinal section through the rotary member and brake.

In the present state of the art thermostats 30 have been found unsatisfactory for use in any place where positive and certain operation is required, and without attention and adjustment. The defect is generally due to the fact that the movement of the thermostatic member, under variations in temperature, is slight, and where its movement is magnified by any system of leverage the connection is variable and uncertain. It is one of the objects of the present invention to obtain a positive and complete control by a 35 very slight movement of the thermostatic or expandible member. This I have accomplished by the construction of a friction brake for normally holding the movable member of the mechanism from operation, 40 said brake being released by a microscopic movement, due to the thermostat.

In the specific construction, A is a rotary member, mounted upon a stationary member B.

C C' are conical and relatively movable brake shoes engaging the opposite ends of the member A. These shoes are clamped between the opposite ends D and E of the 55 thermostatic member which, as shown, is

formed of a U-shaped metallic bar F, having a bar G of a different metal with a higher coefficient of expansion arranged between the legs thereof. The rotary member A is preferably provided with a series of ratchet teeth for engagement with a dog or pawl H upon a member I of an electric switch. This member I, as shown, is secured to a rotary shank J, having an operating button K at its upper end, and a spring L coiled thereon 60 for exerting a rotative tension sufficient to throw the switch. In the normal position of the parts, the pawl H is engaged with one of the ratchet teeth of the member A and is held thereby against the tension of the 65 spring L in contact with the coöperating electric contact M of the switch.

In operation, whenever there is a rise in temperature sufficient to cause an expansion of the bar G, this will cause a very slight 70 spreading of the legs D and E of the U-shaped bar F, with the result that pressure on the friction shoes C and C' is released, and this results in pressure upon the member A. This will permit the tension of the 75 spring L to rotate the shank J, revolving the member A to disengage the dog H and permitting the contact I to separate from the coöperating contact M. To adjust or set the instrument, a member M, having a threaded 80 shank O is preferably arranged intermediate one of the legs E and the friction shoe C'. By turning the threaded shank the pressure on the shoe C' may be altered, and when once adjusted the parts are rigidly locked 85 by a nut P.

This construction of thermostat is particularly applicable to electrically-heated sad irons, as illustrated in Fig. 3. In this construction, the member F is bolted directly to the heating unit, and the thermostat is set so that the normal heating of the iron will not release the switch, but any rise in temperature above normal, even if only a few degrees, will release the brake, and permit the automatic cut-off of the switch.

To avoid danger of a slow opening of the switch, the contact member I' is preferably attached to the member I, so as to have a slight lost motion thereon. Thus, when the member I is first released, it will permit a certain amount of movement before separating the contact I' from the coöperating contact M.

What we claim as our invention is:

1. A thermostat, comprising a movable member, a friction lock for said member, and means operating upon a variation in temperature for releasing said lock. 35
2. A thermostat, comprising an automatically-movable member, a friction lock for holding said member, and means operated upon a change in temperature for releasing said lock. 40
- 10 3. A thermostat, comprising an automatically-movable member, a friction shoe bearing upon said member, and an expansible member normally holding said shoe in locking engagement with said movable member 45
- 15 adapted to release the same at a predetermined temperature variation. 50
4. A thermostat comprising a rotary member, friction shoes engaging opposite sides of said member, an expansible member normally clamping said shoes but adapted to release the same upon rise in temperature to a predetermined point, and an automatically-movable member normally held from movement by engagement with said rotary member. 55
- 20 5. A thermostat comprising an automatically-operating member, a rotary ratchet member, a pawl on said automatically operating member engaging said ratchet member, a friction shoe for holding said ratchet member from rotation, and an expansible member normally clamping said shoe and adapted to release the same upon rise in temperature to a predetermined point. 60
- 25
6. A thermostat, comprising an automatically-operated member, a rotary ratchet member, a pawl on the movable member of said automatically operated member engageable with said ratchet member, a friction shoe bearing on said ratchet member, a U-shaped expansible thermostatic member embracing said rotary ratchet member and shoe and normally clamping the same together. 65
7. A thermostat comprising a U-shaped member, a member having a greater co-efficient of expansion extending between the legs of the U, a rotary member embraced by said U-shaped member, a friction shoe bearing on the end of said rotary member, and an adjustable member between said friction shoe and one leg of said U-shaped member, for the purpose described. 70
8. A thermostat comprising a rotatable member, a friction lock for holding said member from rotation, means operating upon a change in temperature for releasing said lock, and an automatically movable member normally held from movement by engagement with said rotary member. 75

In testimony whereof we affix our signatures in presence of two witnesses.
